UNITED STATES PATENT OFFICE.

ASA G. DELPH AND ROBERT C. HEMPHILL, OF KANSAS CITY, MISSOURI.

LOCK.

1,422,936.

Specification of Letters Patent.

Patented July 18, 1922.

Application filed July 5, 1921. Serial No. 482,373.

To all whom it may concern:

Be it known that we, ASA G. DELPH and ROBERT C. HEMPHILL, citizens of the United States, residing at Kansas City, in the county of Jackson and State of Missouri, have invented certain new and useful Improvements in Locks; and we do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to locks for doors and windows and the primary object thereof is to provide an efficient means for locking a window or door, the means being so constructed that it will be normally held out of operative position; that is, unless the window or door is tampered with, the lock will not become effective but in the event that a burglar or other unauthorized person attempts to pry open the door or window, the lock will be effective to frustrate the attempt at illegal entry.

The invention contemplates broadly the conception of means for normally retracting a bolt or bolts but which will release the bolt or bolts whenever any one attempts to pry open the door or window.

The novel construction of the invention as well as the preferred forms of the same will be apparent by reference to the following description in connection with the accompanying drawings, in which—

Fig. 1 is a perspective view of the outside of a window frame and window sash equipped with our invention.

Fig. 2 is an inside view of the same.

Fig. 3 is a sectional view on the line 3—3 of Fig. 2.

Fig. 4 is an outside view of a door frame and door to which our invention is applied.

Fig. 5 is an inside view of the same, and

Fig. 6 is a sectional view on the line 6—6 of Fig. 5.

In the construction shown in Figs. 1, 2 and 3, 1 is a window frame provided with the usual sash 2. The bottom rail 3 of the sash carries on the outside face a plate 4, which extends practically the length of the rail 3 and is connected to an equalizing bar 5 through the medium of the elbow levers or cranks 6 and 7 so that when one portion of

the plate 4 is raised, the remaining portion will move to the same extent.

Extending through the rail 3 is a latch 8, which is fastened to the bar 4 and the latch operates in the slot 9. The latch 8 is provided with an end 10, adapted to be engaged by the hooked ends 11 and 12 of the normally retracted, spring-actuated bolts 13 and 14, the springs 15 and 16 having a tendency to project the bolts in opposite directions to engage any one of a number of recesses 17 in the side rails 18 and 19 of the window frame 1.

When the parts are in the position shown in Figs. 1, 2 and 3 and any one attempts to pry open the window from the outside, the raising of the plate 4 will raise the latch 8, releasing the hooked ends 11 and 12 of the bolts 13 and 14 so that the springs 15 and 16 can project them into the openings 17 in the rails of the window frame, thereby constituting a lock which will prevent the sash from being raised. The bolts will normally be retracted by engaging the end 10 of the latch 8 so that the window may be raised and lowered from the inside without fear of springing the bolts. The bolts will only open when released from engagement with the end 10 of the latch 8.

In Figs. 4, 5 and 6, a bar 20 will be fastened to the outside of the door 21 and it may be provided with an equalizing link 22 connected to the bar 20 by the elbow levers 23 and 24. The bar 20 is also provided with a latch 25, connected to the bar 26 slidable in the guides 27 and 28 on the inside of the door and having a head 29, which constitutes an abutment and spacer between the spring-pressed rods 30 and 31, the ends of which engage the hooked portions 32 and 33 of spring-pressed bolts 34 and 35 at right angles to the rods 30 and 31. Therefore, when the plate 20 is pried in an attempt to irregularly open the door, the bar 26 will have a reciprocatory motion imparted to it through the medium of the connecting link 25, to move the head 29 out of engagement with the ends of the bars 30 and 31 so that they may be spring-actuated to withdraw the ends from engagement with the hooked portions 32 and 33 of the bolts 34 and 35, allowing the springs 36 and 37 to project the bolts into the keepers 38 and 39 in the door frame 40, thereby locking the door so that it cannot be opened by prying.

It will also be apparent that the lock will function whenever the guard bars 4 or 20 are tampered with or if any part of the equalizing mechanism is tampered with.

5 What we claim and desire to secure by Letters-Patent is:

1. In combination, a frame having an opening and a movable closer for the opening, normally retracted, spring-actuated bolts on 10 one side of the movable closer, a plate on the other side of the movable closer extending to the edge thereof and adapted to normally lie in juxtaposition to one edge of the frame, and means co-operating with the plate 15 for normally holding the bolts in retracted position but responsive to movement of the plate for releasing said bolts to engage the frame.
2. The combination with a frame having 20 an opening and a movable closer for the same, of a plate on one side of the closer, normally retracted, spring-actuated bolts on the other side of the closer, means connected

to the plate and extending through the closer for releasing said bolts, and means on the 25 frame for engagement by said bolts.

3. In a device of the class described, a window sash locking device comprising a plate, a latch carried by the plate to extend through the sash, and normally retractable, spring- 30 actuated bolts releasably engaging one end of the latch.

4. In combination with a window sash, a plate carried by the bottom rail thereof, a latch extending through the bottom rail, 35 oppositely urged bolts carried by the bottom rail and normally engaging the latch, the plate being effective to release the latch from engagement with the bolts to permit them to move into functional position, and keepers 40 for engagement by said bolts.

In testimony whereof we affix our signatures.

ASA G. DELPH.
ROBERT C. HEMPHILL.
